UNITED STATES PATENT OFFICE.

WALTER L. TRUEBLOOD, OF DES MOINES, IOWA.

DESIGN FOR A BADGE.

42,680.

Specification for Design. Patented June 25, 1912.

Application filed April 17, 1912. Serial No. 691,508. Term of patent 7 years.

To all whom it may concern:

Be it known that I, WALTER L. TRUEBLOOD, a citizen of the United States, residing at Des Moines, in the county of Polk, State of Iowa, have invented a new, original, and ornamental Design for Badges, of which the following is a specification, reference being had to the accompanying drawing, forming a part thereof.

The figure is a front elevation of a badge showing my new design.

I claim:

The ornamental design for a badge as shown.

In testimony whereof I hereunto affix my signature in the presence of two witnesses this 10 day of April, 1912.

W. L. TRUEBLOOD.
